J. W. RUDOLPH,
WEIGHER'S RAPID WEIGHT STAMPER,
APPLICATION FILED APR. 30, 1921.

1,382,015.

Patented June 21, 1921.

Fig. 2

INVENTOR,
James W. Rudolph,
BY Howard S. Smith,
His ATTORNEY.

UNITED STATES PATENT OFFICE.

JAMES W. RUDOLPH, OF DAYTON, OHIO.

WEIGHER'S RAPID WEIGHT-STAMPER.

1,382,015.

Specification of Letters Patent. Patented June 21, 1921.

Application filed April 30, 1921. Serial No. 465,738.

To all whom it may concern:

Be it known that I, JAMES W. RUDOLPH, a citizen of the United States, residing in the city of Dayton, in the county of Montgomery and State of Ohio, have invented certain new and useful Improvements in Weighers' Rapid Weight-Stamper, of which the following is a specification.

The principal object of my invention is to provide for weighers in biscuit-making, cake-making and other establishments, a rapid weight stamper by which boxes and cans may be quickly and efficiently stamped by a less number of employees than are now required for that purpose. The stamper can be easily attached to the back of the fingers and the wrist, to permit any one of a series of rubber stamps to be instantly brought to a position by a bending movement of a finger or the back of the hand to stamp any weight desired on a box, can or other object.

Other important and incidental objects will be brought out in the following specification and particularly set forth in the subjoined claims.

In the accompanying drawings, Figure 1 is a plan view of the rear portion of the fingers and wrist of a human hand, showing how my rapid weight stamper is applied thereto. And Fig. 2 is a side view of that hand, showing how one of the rubber stamps is brought to a weight stamping position by the bending movement of a finger.

Throughout the specification and drawings, similar reference characters denote corresponding parts.

Referring to the accompanying drawings for a detailed description of the preferred form of embodiment of my invention, the numeral 1 designates the wrist of a human hand over which is slipped a cuff 2 from which there project forwardly strips 3 that terminate at their outer ends in thimble portions 4. The latter are adapted to be slipped over the tips of the fingers, so that the strips 3 may run from said thimble portions 4 to the cuff 2 over the back parts of the fingers and wrist, leaving the palm of the hand bare. The entire stamper preferably consists of one piece of rubber, and may be quickly and easily applied to the hand in a glove-like manner.

There are preferably four of these strips

3, one for each finger, and to the back portion of each strip there is glued, or otherwise suitably secured, a series of rubber stamps 5. There are seven of these stamps attached to each strip, although a greater or a less number may be provided without departing from the spirit of the invention.

The first four stamps 5 on the strip 3 affixed to the first finger, contain the following respective designations:

"NT-WT" "NT-WT" "NT-WT" "NT-WT" 65
6, 6 $\frac{1}{2}$, 6 $\frac{1}{2}$, 6 $\frac{1}{2}$, and 6 $\frac{1}{2}$.

The numbers below the designation "NT-WT" on the first four stamps on the second strip 3, are "7," "7 $\frac{1}{4}$," "7 $\frac{1}{2}$ " and "7 $\frac{3}{4}$ "; those on the first four stamps of the third strip 3 are "8," "8 $\frac{1}{4}$," "8 $\frac{1}{2}$ " and "8 $\frac{3}{4}$ "; and those on the first four stamps on the fourth strip 3 are "9," "9 $\frac{1}{4}$," "9 $\frac{1}{2}$ " and "9 $\frac{3}{4}$." Below the first four stamps on the strips 3, the numbers run crosswise in the following progression, "10," "10 $\frac{1}{2}$," "11," "11 $\frac{1}{2}$," etc., up to "15 $\frac{1}{2}$." While I have illustrated the stamps 5 as containing the above numbers below the designation "NT-WT," any other numbers and designations may be employed without departing from the spirit of the invention.

To stamp any one of the above designations of net weight upon a can or box, the finger holding the particular stamp 5 to be used for that purpose, is bent as shown in Fig. 2 to force that stamp, which is designated as "A" in that figure, against the surface 6 to leave its impression there. Weighers can acquire such great skill in the use of my rapid weight stamper, that they can stamp the correct weights upon boxes and cans with great speed and a minimum of effort. In a short time the locations of the stamps to be used become as familiar to them, as the keys on a typewriter become familiar to an efficient operator of that machine.

Having described my invention, I claim:

1. A device of the type described comprising a cuff adapted to be slipped over the wrist of a human hand, and stamping means attachable to the back portions of the fingers of said hand, projecting forwardly from said cuff for the purpose specified.

2. A device of the type described comprising a cuff adapted to be slipped over the wrist of a human hand, strips projecting forwardly along the back portions of the fingers

of said hand, and a series of stamps on the back portion of each strip, for the purpose specified.

3. A device of the type described comprising a cuff adapted to be slipped over the wrist of a human hand, strips projecting forwardly along the back portions of the fingers of said hand, a thimble portion on the front end of each strip to be applied to

the tip of its respective finger, and a series 10 of stamps attached to the back portion of each strip, for the purpose specified.

In testimony whereof I have hereunto set my hand this 27th day of April, 1921.

JAMES W. RUDOLPH.

Witness:

HOWARD S. SMITH.
